UNITED STATES PATENT OFFICE

170,659

ROLLING PIN HOLDER OR SIMILAR ARTICLE

Arthur A. Powers, Sheridan, Wyo.

Application January 25, 1952, Serial No. 18,221

Term of patent 14 years

(Cl. D44—29)

To all whom it may concern:

Be it known that I, Arthur A. Powers, a citizen of the United States, and a resident of the city of Sheridan, in the county of Sheridan and State of Wyoming, have invented a new, original, and ornamental Design for a Rolling Pin Holder, or Similar Article, of which the following is a specification, reference being had to the accompanying drawing forming a part thereof.

On the drawing:

Figure 1 is a top plan view of the rolling pin holder, or similar article, showing my new design;

Figure 2 is an elevational view; and

Figure 3 is an end elevational view thereof.

I claim:

The ornamental design for a rolling pin holder, or similar article, as shown.

ARTHUR A. POWERS.
